CLAIM

The ornamental design for a greeting card with mobile ornaments, as shown and described.

DESCRIPTION

FIG. 1 is a perspective view of the greeting card with mobile ornaments of the present invention, in an open position.

FIG. 2 is a front view of the greeting card with mobile ornaments of FIG. 1.

FIG. 3 is a rear view of the greeting card with mobile ornaments of FIG. 1.

FIG. 4 is a left side view of the greeting card with mobile ornaments of FIG. 1.

FIG. 5 is a right side view of the greeting card with mobile ornaments of FIG. 1.

FIG. 6 is a top view of the greeting card with mobile ornaments of FIG. 1.

FIG. 7 is a bottom view of the greeting card with mobile ornaments of FIG. 1; and,

FIG. 8 is a front perspective view of the greeting card with mobile ornaments of FIG. 1, in a closed position.

The broken line showing of portions of the greeting card with mobile ornaments is included for the purpose of illustrating environmental structure and forms no part of the claimed design.
